Roger Achard, Bordeaux, France, assignor to Les
Heritiers de Marie Brizard & Roger, Achard,
Glotin & Cie, Bordeaux, France, a corporation of France

Application September 24, 1951, Serial No. 16,728
Term of patent 7 years

(Cl. D58—9)

To all whom it may concern:

Be it known that I, Roger Achard, a citizen of France, residing at Bordeaux (Gironde), France, have invented a new, original, and ornamental Design for a Bottle, of which the following is a specification, reference being had to the accompanying drawing, forming part thereof.

In the drawing

Fig. 1 is a front elevational view of a bottle, showing my new design;

Fig. 2 is a side elevational view thereof;

Fig. 3 is a rear elevational view; and

Fig. 4 is a top plan view.

I claim:

The ornamental design for a bottle, substantially as shown.

ROGER ACHARD.
